UNITED STATES PATENT OFFICE.

ELMER E. CORNWELL AND JOSEPH H. McCREADY, OF OKMULGEE, OKLAHOMA.

BURNER.

Application filed May 27, 1922. Serial No. 564,025.

To all whom it may concern:

Be it known that we, ELMER E. CORNWELL and JOSEPH H. McCREADY, citizens of the United States, and residents of Okmulgee, 5 in the county of Okmulgee and State of Oklahoma, have invented certain new and useful Improvements in Burners, of which the following is a specification.

This invention relates to an improvement 10 in gas burners of the type forming the subject-matter of our Patents Nos. 1,405,100 and 1,405,101.

The object of our invention is to provide a burner of this character wherein the 15 proportion of air and gas may be conveniently regulated so as to insure a generation of a highly combustible mixture and under varying conditions thereby insuring at all times a generation of a high degree of heat 20 and in general an efficient operation on part of the burner.

A further object is to provide a burner structure wherein the mixing chamber and the gas chamber are highly organized and 25 are positively supported in adjusted relation with respect to each other.

Another object is to provide a device of 30 this character which is of simple and durable construction, reliable and efficient in operation and easy and comparatively inexpensive to manufacture.

Other objects and advantages of the invention reside in certain novel features of the construction, combination and arrangement of parts which will be hereinafter 35 more fully described and particularly pointed out in the appended claims, reference being had to the accompanying drawings forming part of this specification, and in 40 which:

Figure 1 is a view in side elevation, showing the preferred embodiment of the invention;

Figure 2 is a view in longitudinal vertical section;

Figure 3 is a view in rear elevation;

Figure 4 is a detail view in elevation of the rotatable damper; and

Figure 5 is a view in elevation of the rear 50 end of the mixing chamber, the fuel chamber and the rotatable damper being removed.

Referring to the drawings, the numeral 10 designates an open ended shell having a section 11 of elliptical cross section and 55 converging toward the free end thereof,

and a section 12 integral with the section 11, the section 12 being circular in cross section and of frusto-conical form. The section 11 constitutes a nozzle and the section 12 constitutes a mixing chamber, as 60 will hereinafter more fully appear.

As shown in Figures 2 and 5, the large end of the section 12 has integrally formed therewith a series of inwardly and radially extending and spaced wings 13, the spaces 65 between the wings being indicated at 14 and constituting air inlet openings. The inner edges of the wings 13 are beveled, as at 13^a to constitute seats, as will be understood.

A fuel chamber designated generally at 15 is arranged in cooperative relation with respect to the mixing chamber constituted by the section 12 of the shell. Preferably the gas chamber comprises an inner cylindrical wall 16, an outer wall made up of a cylindrical section 17 and an integral frusto-conical section 18 and end walls 19 and 20, both of which are integrally formed with the inner wall 16, the end wall 19 being also integrally formed with the cylindrical section 17 of the outer wall and the end wall 20 being also cylindrically formed with the frusto-conical section 18 of the outer wall whereby the walls define an enclosed fuel space 21 to which gas is supplied to any suitable source through a connection 22. The end wall 20 of the gas chamber is disposed at the outlet end of the chamber and it is provided with a multiplicity of discharge openings or orifices 23 arranged in circular series. At the discharge or outlet end of the gas chamber the section 18 of the outer wall is provided with a shouldered seat 24 which engages 95 the seats 13^a of the wings 13 in assembly and the gas chamber is supported in this manner and in proper relation with respect to the mixing chamber by means of straps or arms 25 secured, as at 26, to the shell 10 and adjustably secured to the gas chamber by means of nuts and bolts 27 carried by the fuel chamber and cooperable with elongated slots 28 provided in the straps or arms 25.

A rotatable damper, designated generally at 30 abuts the large end of the mixing chamber 12 and encircles the adjacent portion of the gas chamber 15. This damper comprises a ring 31 having integrally 100 105 110

formed therewith a series of spaces and inwardly extending wings 32 corresponding in structure and in arrangement to the wings 13 and abutting these wings 13 in assembly. The inner edges 33 of the wings 32 ride in the annular groove or channel 34 provided in the section 18 of the gas chamber and an annular rib 35 overlaps the large end of the shell 10 whereby the damper is constrained to rotary movement. A handle or lug 36 facilitates manipulation of the damper. It is obvious that the damper may be adjusted so that its wings 32 are staggered with respect to the wings 13 and consequently lie across the air inlet openings 14 preventing inflow of air through these openings or on the other hand the damper may be so adjusted as to dispose the wings 32 in alinement with the wings 13 leaving the spaces 14 open and permitting flow of air through these spaces. A swinging damper 38 controlled by a set screw 37 regulates the flow of air through the axial opening of the gas chamber.

25 In operation, gas being supplied to the space 21 it is discharged in the form of a multiplicity of jets from the discharge openings 23 and into the mixing chamber 12 wherein it commingles with the air flowing through the axial opening of the gas chamber and flowing through the inlet opening 14 if the chamber 30 be opened. The chamber 30 may be adjusted to give the mixture the desired proportion of air so as to adapt the burner to varying conditions. The mixture is in the main formed in the chamber 12 but the commingling action progresses in the chamber defined by the section 11 which also constitutes the nozzle of the burner. In 35 this manner a highly combustible mixture may be obtained under various conditions.

We claim:

1. In a burner, an open ended shell constituting the mixing chamber and the nozzle of the burner and having a large section of 45 frusto-conical form and of circular cross section and a small section of elliptical cross section, the large section merging at its small end into the small section and the small section tapering toward its outlet end, and a 50 gas chamber arranged at the open end of the large section and made up of an inner cylindrical wall defining an axial air passage, an outer wall including a cylindrical section and a frusto conical section, the frusto conical section converging toward the large end of the shell and coacting with this large end to define an air inlet into said shell, said gas chamber also having end walls integral with the inner and outer walls to define 60 therewith an enclosed gas space, the end wall adjacent the shell having a circular series of discharge openings. 55

2. In a burner, a mixing chamber having a series of spaced and inwardly extending wings at its inlet end, the wings defining air inlet openings, a gas chamber engaged with the inner ends of the wings of the mixing chamber, and a rotatable damper abutting the inlet end of the mixing chamber and 65 encircling the gas chamber and comprising a ring having a series of wings spaced from each other and extending inwardly and co-operable with the wings of the mixing chamber to regulate the flow of air through the air inlet openings, said gas chamber having a channel in which the inner ends of the wings of the damper are received, the damper having an annular rib overlapping the 70 adjacent end of the mixing chamber. 75
